UNITED STATES PATENT OFFICE.

CHARLES L. RAYFIELD, OF CHICAGO, ILLINOIS.

CARBURETER.

1,401,555.

Specification of Letters Patent. Patented Dec. 27, 1921.

Application filed June 21, 1917. Serial No. 176,187.

To all whom it may concern:

Be it known that I, CHARLES L. RAYFIELD, a citizen of the United States, residing at Chicago, in the county of Cook and State 5 of Illinois, have invented certain new and useful Improvements in Carbureters, of which the following is a specification.

One of the objects of my invention is to provide automatically controlled means in a 10 carbureter for producing the charge intake of internal combustion engines, whereby, especially to provide suitable qualities of fuel charges, at times of starting the engine when it is cold, to compensate for the increase of viscosity of the fuel; the larger 15 oxygen content of the cooled air; condensation of the charge, and other results produced by relatively low temperature.

Another object of my invention is to provide 20 means in a carbureter, to automatically adjust the parts thereof, as the engine cools off to atmospheric temperature, whereby suitable conditions will thereby be established to admit proper proportions of 25 liquid fuel and air, appropriate for, and preliminary to starting of the engine, and parts, arranged to vary the valve adjustment, responsive directly to the heat evolved by operation of the engine.

30 And still another object of my invention is to provide a carbureter having operative parts adjusted to produce a quality of mixture suitable for given temperatures of the engine, by affecting a valve for this purpose, 35 and means, responsive to the heat given off by the engine to modify the adjustment of said valve.

Other and more specific objects of my invention will become readily apparent, to 40 persons skilled in the art, from a consideration of the following description when taken in conjunction with the drawing, which shows a central vertical section of a conventional representation of a carbureter and a 45 part of the exhaust pipe, with my thermo-responsive device partly inserted within the exhaust pipe, for varying the resistance to operation of the air admitting valve of the carbureter.

50 At the time of starting an internal combustion engine it is colder, of course, than it is when it has been heated to a sufficient

operative temperature. At such time the liquid fuel, such as gasoline, is below the temperature at which it is maintained during normal working operation of the engine. When the liquid fuel is cold it is more viscous than when it is warm. Therefore, the same quantity of such fluid will not pass through a given orifice, under the same 55 pressure, as when it is heated to a higher temperature. It follows, then, that a smaller portion of fluid, or gasoline, passing through a fixed orifice, other conditions being unchanged, will provide an attenuated 60 or sub-normal mixture, of a quality below that required for normal operation. When cold, the air is specifically heavier than when warm, therefore, a given volume of air which will pass through a given orifice 65 under a given pressure will be of greater mass than when it is warmer.

It is the mass of air and not its volume that determines its oxygen content and it is the proportion of oxygen to hydrocarbon 70 that determines the quality of mixture, and not the volume of air per given volume of gasoline. From the above statement it will be readily deduced that with the usual carbureter adjusted for normal operation, there 75 will be admitted into the cylinders of an engine a smaller quantity of gasoline and a greater quantity of oxygen at the time when the engine is being started, thus producing at such time a lean or subnormal attenuation of the fuel charges.

In the accompanying drawing showing a vertical section of the device, I have illustrated one embodiment of my invention, for the purpose of clear disclosure, reserving, 90 however, to myself, the right to change or vary the structure to any extent or in any direction, within the scope of the appended claims.

The casing 5 incloses the mixing chamber 95 6, the float chamber 7 and the chamber 8, within which the temperature-responsive device 9 is contained. This chamber is separably secured to the main body part of the carbureter for convenient application to the 100 engine. The casing 8 is threaded on the outside, as at 10, for a nut 11 whereby it may be screwed into a threaded orifice provided in the exhaust pipe 12, as the screw

threaded flange 13 thereof, to a greater or less distance as may be desired so as to expose a greater or less surface to the heating effect of the hot exhaust products of combustion. When the casing 8 has been introduced to the proper extent within the exhaust pipe, the nut 11 is tightened and this helps to support the carburetor in position. The heat responsive device 9 in the casing 8, in this particular embodiment, takes the form of a bellows diaphragm, or diaphragm structure, capable of considerable, relative axial elongation and contraction. It is air tight and imprisons air or other fluid having a critical temperature expansion.

The air intake opening 14 of the carburetor is normally closed by an air valve 15. The spring 16, which moves the valve 20 toward closed position may be adjusted by the bearing nut 17, which surrounds the valve stem 18, and by which the valve stem is guided. A supplemental spring 19 connects the valve 15 to the axially movable 25 diaphragm structure 9. This spring tends to close the valve, when the diaphragm structure is contracted, as shown, and in this respect it supplements the action of the valve spring 16. The valve is therefore 30 yieldingly held closed by the combined action of the springs 16 and 19 when the expandible medium, gas or air, within the diaphragm structure, is below a given temperature. When the imprisoned expandible 35 medium is heated, as by the heat emanating from an engine, and in this particular case by the hot products of combustion passing through the exhaust pipe, the diaphragm structure 9 will be expanded, thereby relaxing the spring 19, by increase of heat, and contracting it by a decrease of heat, which will consequently reduce and increase the stress with which the valve 15 is held closed. Thus when the spring is relaxed 40 the valve 15 will be more easily operable by the suction effect of the engine and it will be held more firmly toward closed position when the temperature of the engine is decreased by the contracting effect of the heat responsive structure.

20 is the spraying nozzle of the carburetor, in communication with the liquid-containing float chamber 7 by an opening 21. The needle valve 22 may be used to control 45 the flow of gasoline into the nozzle and 26 is the throttle.

Primary air passages, around the nozzle, are provided by the openings 23, of which there may be any desired number of suitable 50 sizes.

The float 24 controls the quantity, or level of the liquid fuel in the float chamber, as usual in such devices.

The operation of the device is as follows:—When the engine is cold, or rela-

tively cold, the air, or other expandible fluids, or gas within the heat-responsive device 9, is cool and contracted, causing contraction of this diaphragm structure. The decrease in volume of the confined medium, 70 resulting from the reduction of temperature, in coöperation with the external atmospheric pressure, will cause contraction of the diaphragm structure. This, of course, as heretofore explained, increases the tension of the spring 19. When the engine shaft is initially rotated, in the act of starting the engine, it will, therefore, require greater suction to be produced by the engine to open the valve 15, to the same extent, as such operation is now opposed by the combined resistance imposed by the springs 16 and 19. Consequently a mixture of suitable quality will be drawn into the cylinder, as the air will be taken in largely through 85 the primary air ports 23. After the engine has been operating for a while, its increased temperature will heat and expand the content of the heat-responsive member 9, causing the free end thereof to be moved downwardly, thereby reducing the tension of the spring 19, whereupon the air supply valve 15 will be more easily opened by the same suction, to supply the proper proportion 90 of air for the normal running of the engine. 95 By this means compensation is made for the reduced temperature of the engine, of the fuel and of the air, at the time of starting and during the time when the temperature of the engine is below that at which it is 100 most efficiently operated, the quality of the charge mixture being automatically maintained, against varying conditions of fuel temperature, as the temperature of the engine increases. The change in the adjustment, due to the hot exhaust gases from the engine will take place very quickly after starting of the engine, as the first few impulses of the hot exhaust gases will be sufficient to cause material expansion of the heat-responsive device, causing it to reduce the resistance imposed by it to the operation 105 of the auxiliary air valve 15. For the foregoing reasons the device serves as an automatic primer in which air is taken into the carburetor largely through the primary air ports 23 until the engine has been properly started after which more or less air will be taken through the port controlled by the valve 15.

While I have herein shown a single embodiment of my invention for the purpose of clear disclosure, it is manifest that changes may be made in the general form and arrangement of the parts within the 110 scope of the appended claims.

Having described my invention, what I claim is:—

A carburetor having an air admitting valve, in combination with a heat-responsive 115

device, normally resisting the opening of said valve, subject to be heated by the hot exhaust gases of an engine to reduce said resistance; a casing, exteriorly threaded and surrounding said responsive device for insertion to a greater or less extent, within a threaded aperture in a conduit carrying the hot gases exhaust from said engine, and a nut surrounding said casing for securing it in adjusted position. 10
In testimony whereof I hereunto set my hand.

CHARLES L. RAYFIELD.
